APPARATUS FOR PRODUCING REINFORCED SHEET MATERIAL

Arthur E. Carlson, Troy, and Joe Baxter, Jr., Franklin, Ohio; said Baxter, Jr., assignor to Carlson

Application August 14, 1950, Serial No. 179,302

20 Claims. (Cl. 154—1.76)

This invention relates to apparatus for producing reinforced sheet material.

In the manufacture of sheet material wherein strength is essential, the item of cost is very important, especially in some industries, for the reason that huge quantities of such material is used. For example, in the manufacture of cartons made from corrugated paper, cardboard and the like, tape is used for holding the seams together. On some types of cartons, woven material having a suitable adhesive applied to one side thereof is used for overlapping the seams and retaining the parts in position. This material is expensive. In lighter weight cartons and boxes, paper having applied thereto an adhesive material, is used for securing the parts together. If a light weight paper is used, there is danger of failure. For many purposes the light weight paper is apt to be inadequate, in which event it is necessary to resort to either a woven fabric or a heavy weight paper having the desired strength. In either case, the cost becomes a very important item.

In Carlson's copending applications for United States Letters Patent, Serial No. 109,482, filed August 10, 1949, for Reinforced Paper Articles, now U. S. Patent No. 2,610,936, and Serial No. 140,532, filed January 25, 1950, for Reinforced Sheet Material, Apparatus for and Method of Producing the Same, now abandoned, a reinforced sheet material has been disclosed for use in the manufacture of boxes, cartons, crates and other uses to which the reinforced sheet material is suitable.

An object of this invention is to provide apparatus for producing the reinforced sheet material disclosed in the aforementioned applications for United States Letters Patent.

Another object of this invention is to produce an apparatus for laying reinforcing ribbons or elements in equally spaced parallel relation transversely across a sheet of material, or rather, a pair of sheets of material, the apparatus being provided with mechanism which permits contraction of the reinforcing elements after they have been placed in position without the reinforcing elements being shorter after contraction than the width of the sheet material.

Another object of this invention is to feed strip material continuously through a device for laying the reinforcing elements in position, the reinforcing elements being placed transversely across the sheet in equally spaced relation.

Another object of this invention is to provide rotatably mounted supports for bobbins, said bobbins being equally spaced circumferentially about the supports. The supports are divisible into two halves, so as to permit removal of one support for the bobbins when emptied, to be replaced by another like support provided with filled bobbins, so as to permit the use of the device for laying the ribbons in position while one support is being re-loaded with filled bobbins.

Another object of this invention is to provide a device for placing reinforcing elements upon the surface of sheet material wherein the reinforcing elements are applied from a plurality of bobbins mounted for rotation about the sheet of material, the reinforcing elements upon leaving the bobbins being passed through a stationary pot of adhesive material to thereby supply adhesive material to the reinforcing elements before the reinforcing elements come into contact with the sheet material.

Other objects and advantages reside in the construction of parts, the combination thereof and the mode of

2

operation, as will become more apparent from the following description.

Referring to the drawings,

Figure 1 is a top plan view of the device for laying the reinforcing elements in position, showing the mandrel in cross section.

Figure 2 is a fragmentary, enlarged view of a portion of the device disclosed in Figure 1.

Figure 3 is a side elevational view of a device for laying the reinforcing elements in position.

Figure 4 is a cross sectional view taken substantially on the line 4—4 of Figure 1.

Figure 5 is a fragmentary view of a tensioning mechanism, partly in cross section.

Fig. 6 is an enlarged view of a fragment of Fig. 4.

The device for manufacturing the reinforced tape includes paper unreeling mechanism, sheet material supporting mandrel and ribbon applying or wrapping mechanism. Each of these will now be described.

Unreeling mechanism

The unreeling mechanism includes a pair of roll supporting devices 20, each provided with diagonally disposed slots 22 adapted to receive arbors 24 extending through the rolls 26 of paper or other sheet material. The rolls 26 of sheet material are supported upon the arbors 24 adapted for sliding and rotating movement in the slots 22. The rolls of paper are also supported upon a pair of feed rollers 30 driven through a suitable gear mechanism by a shaft 32 from a motor 34 through a suitable speed reducing mechanism 36. Two rollers 30 are mounted in close proximity to each other, so that as the sheet material is unwound from the rolls 26, the sheet material passes over the rollers 30 and between the rollers so as to be fed downwardly through a slot provided therefor in a support 38, which may represent a floor or any other suitable support, supported in any suitable manner. Due to the fact that the sheet material is quite wide, for example on the order of four feet, the support 38 must be located a considerable distance above the ribbon applying mechanism, in order to cause the sheet material to be formed into the proper curvature that takes place upon a mandrel, which will now be described.

Sheet material supporting mandrel

The sheet material supporting mandrel 41 consists of a pair of curved plate members 40, secured together along the margins 42, and terminates in a substantially pointed portion 44. The mandrel is supported by V-brackets 46 attached to a support 38. After the sheet material 50 passes between the rollers 30, the two sheets are separated so that one is located on one side of the mandrel 41 and the other is located on the opposite side of the mandrel. As the sheets 50 advance over the mandrel, they eventually are curved, so as to have a curvature corresponding to the curvature of the mandrel. The width of the sheet is slightly less than the width of the mandrel, for reasons that will appear more fully later. This difference between the width of the sheets and the width of the mandrel is best seen in Figure 1. The mandrel 41, together with the sheets of material to be reinforced, extends downwardly through a ribbon applying or wrapping mechanism.

Ribbon applying or wrapping mechanism

The ribbon applying mechanism includes an internally toothed gear member 60, driven by a pinion 62 keyed to a shaft 64 projecting upwardly from a gear reducing box 66 driven from an electric motor 68. The gear member 60 has fixedly attached thereto a ring 70 by means of a plurality of bolts 72. The ring 70 is provided with an annular bevelled surface 74, forming a race resting upon a plurality of conical rollers or bearings 76 journaled upon a shaft 78, mounted in a bracket 80 resting upon the support or floor 82. At least three or more of these roller bearings are required to support the internally toothed gear member 60 and the ring 70. The ring 70 is provided with an annular channel 84 adapted to support a pair of semi-circular bobbin supporting members 86. The two halves forming the bobbin supporting ring are held together by suitable bolts 88 extending

across the seam 89 between the two members 86. Each member 86 supports a plurality of diagonally disposed spindles 90 and 92, the spindles 90 extending through suitable apertures in the annular inclined portion 94 of member 86. The spindles 92 extend through suitable apertures in the annular inclined portion 96 of member 86. Each of the spindles 90 and 92 supports a spool or bobbin 100 containing ribbons or reinforcing elements 101. Each of these reinforcing elements consist of a plurality of filaments that may be made from synthetic material, such as rayon or nylon.

The device may be used for producing the reinforced sheet material disclosed in the aforementioned copending applications for United States Letters Patent Serial No. 109,482, filed August 10, 1949, for Reinforced Paper Articles, and Serial No. 140,532, filed January 25, 1950, for Reinforced Sheet Material, Apparatus for and Method of Producing the Same. The material wound upon the spools or bobbins need not necessarily consist of the reinforcing elements described above; but may consist of any other type of reinforcing members for use in reinforcing the sheet material, as for example, cord, string or other types of ribbon-like material, as the particular type of reinforcing elements is immaterial as far as the operation of this device is concerned. The semi-cylindrical supporting members 86 are mounted in the channel 84 and clamped into position by a clamping member 102, tightened in position by bolts 104 having a wrench engaging portion 106, mounted on the outer periphery of the annular ring 70.

An inwardly directed semi-annular flange 120 on each member 86 supports a plurality of resiliently mounted tensioning arms 122 and 124, the arms 122 being used in connection with the reinforcing elements 101 withdrawn from the bobbins 100 mounted on the spindles 90 and the arms 124 being used in connection with the reinforcing elements withdrawn from the other series of bobbins.

Bosses 130 mounted upon each member 86 have rotatably mounted therein a flexible shaft 132, there being one flexible shaft for each of the semi-circular members 86. This flexible shaft may be made from resilient material such as rubber or any other suitable material. The flexible shaft may be rotated through an angle of 45°, more or less. A plurality of arms 134, one for each of the bosses 130, are each provided with a bifurcated end 136, each furcation being provided with an aperture through which the flexible shaft 132 passes. The furcations straddle the bosses 130 and are fixedly attached to the flexible shaft 132. By this arrangement, it is possible to adjust the angular position of the arms 134 by merely rotating the flexible shaft 132.

The outer end of each arm 134 has fixedly attached thereto a curved arm 140, provided with an eye 142 and a second eye 144 through which the reinforcing elements 101 pass, there being one reinforcing element for each arm 134. When the arms 134 are actuated into the position shown to the left of Figure 4, the eyes 142 and 144 are located in a toroidal glue pot 150, fixedly mounted so as to remain stationary when the machine is in use. The glue pot is generated by a substantially C-shaped generatrix traveling through a circular path. The C is slightly tilted, so that one edge of the opening of the glue pot is located substantially above the center of the glue pot and the other edge down from the center on the inner side of the glue pot to provide an annular opening 152.

As may best be seen by referring to Figure 4, the glue pot 150 has been so designed that as the arms 134 and 140 are rotated, the adhesive material in the glue pot will also tend to rotate and, due to the centrifugal force of a rotating body, will tend to move outwardly. That being the case, the mouth 152 is angularly disposed so as to provide a lip 153, preventing the adhesive from flowing over the edge of the glue pot 150. Glue pot 150 is mounted upon stationary supports 154 for securing the glue pot 150 to a similar but larger overflow reservoir 156.

The sheet material is gradually fed over the mandrel 41 at a constant rate of speed. While this takes place, the gear member 60 and the parts supported thereby are rotated, so as to wind the reinforcing elements around the sheet material and the margin 42 of the mandrel 41, the reinforcing elements having first been secured in any suitable manner to the sheet material. The reinforcing

elements cause the sheet material to be pressed against the mandrel, thereby causing the sheet material to have the same curvature as the underlying contour of the mandrel. The reinforcing elements passing through the adhesive material in the glue pot 150 are coated with adhesive material. As a matter of fact, the adhesive material is preferably of such a consistency that the adhesive material is drawn by capillary attraction between the interstices between the filaments constituting each reinforcing element. The operation continues until it is necessary to stop the machine, either to replenish the supply of paper or to replenish the exhausted supply of reinforcing elements on the bobbins. When the bobbins supported upon the members 86 are exhausted, a like member 86a, (only one of which has been shown) loaded with a new supply of bobbins, may be substituted for the members 86 supporting the exhausted bobbins. In order to maintain balance, the amount of material on the bobbins on one member 86 should be substantially equal to the supply of material on the bobbins on the other member 86.

Upon stopping the machine, it is desirable to first rotate the flexible shaft 132 through an angle sufficient to actuate the arms 134 and the parts carried thereby from the position shown to the left of Figure 4 to that shown to the right of Figure 4, so as to cause these parts to clear the glue pot. As a matter of fact, whenever stopping the machine, it is desirable to remove these parts from the glue pot so as to remove the reinforcing elements out of contact with the glue pot. Otherwise, the reinforcing elements resting upon the edge of the glue pot will adhere to the edge thereof. After the reinforcing elements have been removed from the glue pot, it is merely necessary to remove the bolts 88 and loosen the bolts or screws 104 to release the clamping members 102 from the members 86 that are to be removed. Then, by lowering the rails 114 carried upon a truck 110 and moving the truck towards the center of the machine, so as to cause the rails 114 to be positioned under one of the members 86 that is to be removed, this member may be raised by means of the jack 112, the truck removed, the rails rotated through an angle of 180°, so as to substitute member 86a having a fresh supply of bobbins thereon in position. This operation is then repeated for the other member 86. The new members are clamped in position by tightening the bolts 104 so as to cause the clamps 102 to securely lock members 86 in position and by inserting the bolts 88 so as to clamp the newly substituted members 86a to each other. The ends of the reinforcing elements are then secured to the ends severed from the exhausted bobbins, after which the flexible shafts are rotated so as to again dip the reinforcing elements into the glue pot. Instead of securing the ends of the new bobbins to the ends from the old bobbins, it may expedite matters to merely secure the ends from the new bobbins in any suitable manner to initiate the wrapping operation. The machine is then ready to be started again to continue the operation.

Member 156 is supported upon a drainage tube 160 and upon a refill tube 162, the upper end of which communicates with the annular glue pot 150. The adhesive that drains into the overflow reservoir 156 is drained from this overflow reservoir through the drainage tube or conduit 160. The adhesive in the glue pot is replenished from a suitable source, not shown, through the refill tube or conduit 162.

When the flexible shaft 132 is in the position shown to the left in Figure 4, the reinforcing elements are pulled through the eyes 142 and 144, so as to be drawn through the adhesive in the glue pot 150, the reinforcing elements upon leaving the glue pot being wrapped around the sheets of material passing over the mandrel 41. In Figure 1 there are approximately 48 bobbins, in other words, there are 48 sources of reinforcing elements. That being the case, 48 elements are wrapped around the sheet material for every revolution of the bobbins about the mandrel. If, for example, three reinforcing elements are desired for every inch of sheet material, the sheet material would then be required to advance sixteen inches downwardly over the mandrel for every revolution of the bobbins about the mandrel. If six ribbons are required per inch, then the sheet material would only advance eight inches for every revolution of the bobbins.

Rather than to change the relative speed of the sheet material and the rotary support for the bobbins, the spac-

ing of the reinforcing elements may be changed by reducing or increasing the number of bobbins. If, for example, it is found desirable to provide reinforced sheet material with only half as many reinforcing elements, in other words, the reinforcing elements being spaced twice as far apart, the number of bobbins could be reduced in half; but in reducing the number of bobbins, the fact should not be overlooked that the reduction should be so made as to maintain balance. The bobbins are preferably diametrically disposed, so as to maintain balance. That being the case, it may be desirable to provide members 86 with additional apertures so that instead of making provision for 48 bobbins, provision may be made for 32 bobbins, or any other suitable number, depending upon the requirements of the finished sheet material.

When using synthetic reinforcing elements or ribbons, it is a characteristic of some material, such as rayon for example, to shrink after being applied to the surface of the sheet material. This shrinkage is caused by moisture in the adhesive applied to the reinforcing elements. In order that the reinforcing elements shall extend from one edge of the sheet material to the opposite edge of the sheet material, it is necessary to provide reinforcing elements that are longer than the width of the sheet material. By providing a mandrel that has a width greater than the width of the sheet material, the reinforcing elements will then extend over the edges of the mandrel beyond the sheet material. Furthermore, the reinforcing elements, upon being wrapped around the sheet material and the mandrel, are integral. That being the case, a pair of rotary cutting discs 170 shown in Figures 3 and 4 and driven by a motor 172 are used in cutting the reinforcing elements so as to sever the reinforcing elements extending from one sheet to the other. Upon the reinforcing elements being cut, the reinforcing elements are permitted to shrink without wrinkling or crumpling the sheet material. The sheet material upon being reinforced, may be subjected to a curing operation for the adhesive, followed by winding the reinforced sheet material into rolls.

By using a flat or oval shaped mandrel, as shown in Figure 1, and rotating the bobbins at a uniform speed around the mandrel, it can readily be seen that the demand for reinforcing elements at the wrapping station varies. At times the rate of speed of the reinforcing elements will be very great and at other times the rate of speed of the wrapping elements at the wrapping station will be very low. This will result in an irregular withdrawal of reinforcing elements from the bobbins, which may result in a whipping action taking place, followed by a tendency for the reinforcing elements to continue unraveling, so as to snarl during the period that the demand at the wrapping position is decelerating. This may take place in the absence of some type of device for compensating for irregular demand at the wrapping station, which compensating device will now be described.

In Figure 5 an attachment adapted for use with the preferred embodiment has been shown. Members 86 may have the portion 94 or 96 provided with tubular members 200, each having a flange 202 abutting one side of the portions 94 or 96, as the case may be, and held in position by a nut 204 threadedly engaging the end of tubular member 200. The upwardly directed portion 206 of tubular member 200 is tapered and supports a bobbin 100. The upper end of the tapering portion 206 is provided with an inwardly directed flange 208, leaving an aperture in the center. A rod 210 extends through the tubular member 200 and terminates in an eye 212, through which the reinforcing element 101 is drawn from the bobbin 100. The rod 210 is mounted for reciprocal movement axially with respect to the tubular support. The end of the rod 210 opposite the eye 212 is attached to a yoke 214 rotatably supporting a cam follower 216 mounted for engagement with a stationary circular cam 218 extending around the wrapping machine. A compression spring 220, having one end seated against the flange 208 and the opposite end abutting the yoke 214, is used in biasing the cam follower 216 into engagement with the cam 218.

It can readily be seen that by this arrangement the reinforcing elements may be withdrawn from the bobbin at a uniform rate of speed, in spite of the fact that the demand for reinforcing elements at the wrapping position is irregular, due to the shape of the mandrel. By properly designing the cam 218, which has merely been

shown schematically and only a portion of it, it can readily be seen that as the demand for reinforcing elements slows up at the wrapping station, the cam 218 projects the rod 210 upwardly so as to continue to withdraw the yarn at a uniform speed from the bobbin 100 and then as the demand at the wrapping station increases, the cam is so designed that the cam follower allows the compression spring 220 to move the eye 212 towards the bobbin into the dotted position shown in Figure 5, thereby compensating for the increased demand at the wrapping station.

Reference is made to the copending application of Arthur E. Carlson, Serial No. 178,434, filed August 9, 1950, and showing related subject matter.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described our invention, we claim:

1. A toroidal glue pot having an annular opening in the inner side near the top thereof, a toroidal overflow reservoir, having a similar annular opening also in the inner side near the top thereof, and means supporting said glue pot within said reservoir and with said annular openings in substantial alignment.

2. The combination of a toroidal glue pot for use in a device for reinforcing sheet material with a toroidal reservoir, said glue pot having an annular opening extending throughout the circumference in the inner side near the top thereof, said reservoir being larger than the glue pot so as to encircle the greater portion of the glue pot and having a similar annular opening also in the inner side and near the top thereof, and means supporting said glue pot within said reservoir with said openings in substantial alignment to cause overflow from said glue pot to be received within said reservoir.

3. A circular support assembly for use in a device for reinforcing sheet material, said assembly including an annular gear ring, a circular member fixedly attached to the gear ring, said circular member having a circular channel, and a pair of bobbin supporting semi-circular members removably secured to said channel, one of said semi-circular members being removable independently of the other semi-circular member so as to permit the removal of one semi-circular member for replacement with a like semi-circular member loaded with a fresh supply of bobbins.

4. A circular support assembly for use in a device for reinforcing sheet material, said assembly including an annular gear ring, a pair of bobbin supporting semi-circular members, means for removably attaching said semi-circular members to the gear ring, one of said semi-circular members being removable independently of the other so as to permit the removal of one semi-circular member when the supply on the bobbins is exhausted for replacement with a like semi-circular member loaded with a fresh supply of bobbins.

5. In a device for use in reinforcing sheet material, said device having a rotatable support provided with a plurality of members for supporting bobbins containing reinforcing elements, the combination including a non-circular mandrel for feeding the sheet material past a station for applying the reinforcing elements to the sheet material, and means for withdrawing the reinforcing elements from the bobbins at a uniform rate of speed and wrapping the reinforcing elements upon the sheet material at an irregular rate of speed, said means including a plurality of movable members each having an eye through which a reinforcing element passes, said eye members having movement such as to change the length of the paths of the reinforcing elements between the bobbins and the sheet material to thereby cause the reinforcing elements to be withdrawn from the bobbins at a substantially uniform speed.

6. In a device for use in reinforcing sheet material, said device having a rotatable support provided with a plurality of members for supporting bobbins containing reinforcing elements, the combination including a non-circular mandrel for feeding the sheet material past a station for applying reinforcing elements to the sheet material, and means for withdrawing the reinforcing ele-

ments from the bobbins at a substantially uniform rate of speed and wrapping the reinforcing elements upon the sheet material at an irregular rate of speed, said means including a plurality of arms each provided with an eye through which a reinforcing element passes, and means for actuating said arms so as to change the distance through which the reinforcing elements pass to thereby cause the withdrawal of the reinforcing elements from the bobbins at a uniform rate of speed and to apply the reinforcing elements to the sheet material at an irregular rate of speed.

7. In a device for reinforcing sheet material, said device having a rotatable support provided with a plurality of members for supporting bobbins containing reinforcing elements, the combination including an oval mandrel for feeding two sheets of material past a station for applying reinforcing elements to the sheet material, and means for withdrawing the reinforcing elements from the bobbins at a uniform rate of speed and wrapping the reinforcing elements upon the sheet material at an irregular rate of speed, said means including a plurality of arms each provided with an eye through which the reinforcing elements pass, a stationary cam concentrically mounted with respect to said rotatable support, a plurality of cam followers, one for each of the arms, said cam followers being mounted for contact with said cam, and means for interconnecting the cam followers to said arms so as to cause the arms to move through paths to thereby change the paths of the reinforcing elements passing from the bobbins to the sheet material.

8. In a device for use in reinforcing sheet material, said device having a rotatable support provided with a plurality of members for supporting bobbins containing reinforcing elements, the combination including a non-circular mandrel for feeding the sheet material past a station for applying reinforcing elements to the sheet material, and means for withdrawing the reinforcing elements from the bobbins at a substantially uniform rate of speed and wrapping the reinforcing elements upon the sheet material at an irregular rate of speed, said means including a plurality of tubular members one for each of the bobbins, said tubular members being mounted upon the rotatable support, rods mounted for reciprocatory movement in said tubular members, there being one rod for each tubular member, each of the rods terminating in an eye through which a reinforcing element passes while being advanced from the bobbin to the station for applying the reinforcing elements, and means for actuating the arms so as to change the path through which the reinforcing elements pass from the bobbins to said station to thereby cause the reinforcing elements to be withdrawn from the bobbins at a substantially uniform rate of speed and applied to the sheet material at an irregular rate of speed.

9. In a device for use in reinforcing sheet material, said device having a rotatable support provided with a plurality of members for supporting bobbins containing reinforcing elements, the combination including a non-circular mandrel for feeding the sheet material past a station for applying reinforcing elements to the sheet material, means for withdrawing the reinforcing elements from the bobbins at a substantially uniform rate of speed and wrapping the reinforcing elements upon the sheet material at an irregular rate of speed, said means including a plurality of tubular members fixedly mounted upon said rotatable support, there being one tubular member for each of the bobbins, a plurality of rods mounted for reciprocatory movement in the tubular members, there being one rod for each tubular member, each of the rods terminating in an eye through which a reinforcing element passes from the bobbin to said station, and means for reciprocating said rods in coordinated relation with the rate of wrapping said reinforcing elements to compensate for the irregular rate of speed that said reinforcing elements are applied to the sheet material.

10. In a device for use in reinforcing sheet material, said device having a rotatable support provided with a plurality of members for supporting bobbins containing reinforcing elements, the combination including a non-circular mandrel for feeding the sheet material past a station for applying reinforcing elements to the sheet material, means for withdrawing the reinforcing elements from the bobbins at a substantially uniform rate of speed and wrapping the reinforcing elements upon the sheet material at an irregular rate of speed, said means includ-

ing a plurality of tubular spindles surrounded by said bobbins, there being one spindle for each bobbin, a plurality of rods mounted for reciprocatory movement in the spindles, there being one rod for each spindle, each of the rods terminating in an eye through which a reinforcing element passes when extending from the bobbin to the station, and cam means for actuating the rods so as to cause the rods to change the paths of the reinforcing elements to thereby change the lengths of the reinforcing elements extending from the bobbins to said station to compensate for the irregular speed at which the reinforcing elements are applied to the sheet material.

11. In a device for use in reinforcing sheet material, said device having a rotatable support provided with a plurality of members for supporting bobbins containing reinforcing elements, the combination including a non-circular mandrel for feeding the sheet material past a station for applying reinforcing elements to the sheet material, means for withdrawing the reinforcing elements from the bobbins at a substantially uniform rate of speed and wrapping the reinforcing elements upon the sheet material at an irregular rate of speed, said means including a plurality of tubular members, one for each of the bobbins, said bobbins surrounding said tubular members, a plurality of rods mounted for reciprocatory movement in the tubular members, there being one rod for each tubular member, each of said rods terminating in an eye through which a reinforcing element passes while being advanced from the bobbin to the station, resilient means for actuating the rods in one direction, and cam means for actuating the rods in the opposite direction, said cam means cooperating with said resilient means to change the paths of the reinforcing elements passing from the bobbins to said station.

12. Apparatus for fabricating reinforced sheet material comprising a base, means on said base defining a work station, means for continuously feeding a web of sheet material through said work station, a supply source of continuous reinforcing material, means supporting said supply source on said base for rotation about said work station in a path defining a plane substantially transverse of the direction of feeding of said web to cause said reinforcing material to wrap around said web and to lie thereon substantially transversely thereof, a container of adhesive material mounted in stationary relation with said base and encircling said work station, means for guiding said reinforcing material from said supply source through said adhesive container prior to contact thereof with said web to cause said reinforcing material to adhere to said web, and means supporting said guiding means for rotation with respect to said base about said work station in correlated relation with said rotating supply source, said guide means extending into said container to cause the adhesive therein to circulate about said work station.

13. In a device for reinforcing sheet material, means for feeding the sheet material past a reinforcing station, rotatably mounted means having a spindle for supporting a bobbin of reinforcing material, means supporting said bobbin and its rotatable supporting means for rotation around said station to unwind said reinforcing material from said bobbin onto said sheet material, a glue pot forming a closed path encircling said station to receive said sheet material therethrough and having a continuous opening encircling said station, means forming a stationary mounting for said glue pot preventing rotation thereof with said supporting means, said glue pot having adhesive material therein, guide means extending through said opening and into said adhesive material for causing the reinforcing material withdrawn from the bobbin to pass through the adhesive material in the glue pot as the bobbin is rotated about the station, and means for effecting rotation of said guide means about said reinforcing station in correlated relation with said rotatably mounted supporting means to cause said guide means to circulate through said pot and thereby to cause said adhesive material to rotate with said rotatably mounted means.

14. In a device for use in reinforcing sheet material moving through a work station, the combination including a rotatable support having a plurality of bobbins mounted thereon and adapted to receive said sheet material therethrough, each of said bobbins having wound thereon reinforcing elements adapted to be wrapped around the sheet material as said rotatable support is rotated, a glue pot forming a closed path encircling said

work station, means forming a stationary support securing said pot against rotation with said support but in generally aligned relation therewith to receive said sheet material therethrough, and guide means mounted for rotation in correlated relation with said rotatable support for guiding the reinforcing elements from said bobbins through said glue pot as the rotatable support is rotated to thereby cause said reinforcing elements to be coated with adhesive material in said glue pot while advancing from said bobbins to said sheet material, said guide means extending into said glue pot for circulation therein with said reinforcing elements to cause adhesive material in said glue pot to circulate therein.

15. In a device for use in reinforcing sheet material traveling along a path, the combination including a rotatable support having a plurality of bobbins mounted thereon and adapted to receive said sheet material therethrough, each of said bobbins containing reinforcing elements adapted to be wrapped around said sheet material when said rotatable support is rotated around said path, a glue pot surrounding said path of travel of said sheet material and having a continuous opening encircling said path, means forming a stationary support securing said pot against rotation with said rotatable support, adjustably mounted guide means mounted upon said rotatable support, said guide means having an operative position and an inoperative position, said guide means when in said operative position extending into said opening to guide the reinforcing elements withdrawn from said bobbins through the adhesive material in said glue pot as said rotatable support is rotated to cause said reinforcing elements to be treated with adhesive material while advancing from said bobbins to said sheet material, and means securing said guide means to said support for rotational movement thereof within said glue pot to cause said adhesive material therein to circulate within said glue pot around said sheet material with said guide means.

16. In a device for use in reinforcing sheet material, the combination including a rotatable support having a plurality of bobbins mounted thereon, means for causing said sheet material to travel through said support, each of said bobbins containing reinforcing elements adapted to be wrapped around the sheet material when the rotatable support is rotated around the sheet material, a glue pot having a continuous opening surrounding the path of travel of said sheet material, means forming a stationary support securing said pot against rotation with said rotatable support, adjustably mounted guide means mounted for rotation about said path, said guide means having an operative position and an inoperative position, said guide means when in said operative position extending into said opening to guide the reinforcing elements withdrawn from said bobbins to pass through the adhesive material in said glue pot as said rotatable support is rotated to cause said reinforcing elements to be treated with adhesive material while advancing from said bobbins to said sheet material, means for effecting rotation of said guide means in correlated relation with said support for rotational movement thereof within said glue pot to cause said adhesive material therein to circulate within said glue pot around said sheet material with said guide means, and means for adjusting said guide means from operative position into inoperative position and vice versa.

17. In a device for applying liquid to continuous length material, the combination including means for supporting a supply of continuous length material, means forming a work station, means for winding the continuous length material around said work station, means forming a liquid container describing a closed path surrounding the work station, said container being stationary in

relation to the winding means, said container having a continuous length opening, rotatably mounted guide means projecting through said opening and into the liquid to guide the continuous length material therethrough and to cause the liquid to rotate around said work station within the stationary container.

18. A permanently stationary liquid container of a shape generated by a substantially C-shaped generatrix moved through a horizontally disposed circular path, the edges of the C cooperating to form a continuous opening through the closed path said opening being of less width than the diameter of said container and being near the top of the container on the inside thereof.

19. In a device for use in transversely reinforcing sheet material advancing along a path, the combination including a rotatable support having a plurality of bobbins mounted thereon, said support being adapted to receive said sheet material therethrough, each of said bobbins containing reinforcing elements adapted to be wound around said sheet material and to be adhesively bonded thereto when said rotatable support is rotated around said advancing sheet material, an adhesive tank with an adhesive supply therein, means forming a stationary support securing said adhesive tank against rotation with said rotatable support, guide means for guiding the reinforcing elements withdrawn from said bobbins to the adhesive and thence to the sheet material, adhesive application means for adhesively treating said elements after leaving said bobbins but before being wound onto said sheet material, and means for rotating said guide means and said adhesive application means for rotational movement in unison with said support.

20. In a device for use in transversely reinforcing sheet material advancing along a path, the combination including a rotatable support having a plurality of bobbins mounted thereon in circumferentially spaced relation, said support being adapted to receive said sheet material therethrough during the travel of the sheet material along said path, each said bobbin containing reinforcing elements adapted to be wound on said sheet material and to be adhesively bonded thereto when said rotatable support is rotated about the advancing sheet material, an adhesive tank with an adhesive supply therein stationarily mounted adjacent said support, guide means for guiding and supporting the reinforcing elements during their travel from said bobbins to the sheet material, adhesive application means associated with said adhesive tank and said guide means for adhesively treating said reinforcing elements during their guided and supported travel after leaving said bobbins but before being wound onto said sheet material, and means for rotating said guide means and said adhesive application means in unison with said support.
